PORATION OF DELAWARE

DEEP WELL FLUID-MOTOR PUMP

Application filed July 21, 1926. Serial No. 123,860.

Our invention relates to deep well fluid-motor pumps and more particularly to such a pump which is adapted for use in a deep petroleum well.

5 In the petroleum industry a great proportion of the oil produced must be pumped from wells averaging between three and six thousand feet in depth and different types of pumps have been devised for pumping the oil from these deep wells.

A common type of pump equipment consists of a reciprocating pump which is placed near the lower end of the well, the barrel thereof being secured to the lower end of a 15 pump tubing which extends upward to the surface of the ground. The plunger of the pump is connected to the lower end of a string of sucker rods which extends to a point above the surface of the ground and 20 is connected to a walking beam, by means of which it and the plunger are reciprocated. This type of pump is not entirely satisfactory, being inefficient in operation and subject to frequent breakdowns which mean a 25 loss of time and production. A great deal of this trouble results from breakage or uncoupling of the string of sucker rods.

Fluid-motor deep well pumps also have 20 been produced. The fluid-motor deep well pump has a fluid-motor operatively associated with a pump and disposed at the lower end of a string of pump tubing in the bottom of a deep well. A small pipe disposed within this pump tubing conveys clean oil under 35 high pressure down from the surface of the ground to the fluid-motor which is motivated thereby to operate the pump which pumps well oil from the bottom of the well upward through the pump tubing.

40 One of the main faults of previously produced fluid-motor deep well pumps is that it is necessary to provide longitudinal eccentric ducts of great length in the body of

drical chamber in the lower end of a string of pump tubing that space is provided in this chamber wherein tubing may be disposed to form all necessary eccentric longitudinal fluid passageways for the operation of the 55 fluid-motor pump.

Another difficulty with previous fluid-motor deep well pumps is in the complete structural separation of the motor and the pump, the pump plunger being moved by the motor 60 piston through a piston rod; thus the effective pressure surface on one end of the piston is smaller during one stroke than during the opposite stroke. Therefore, when the diameter of the pump is made smaller than 65 that of the motor cylinder in order to increase the unit area pressure applied to the pumped fluid by a given unit area pressure in the operating fluid, a different increase is effected for a stroke in one direction than in 70 the other direction.

It is therefore another object of our invention to provide a fluid-motor deep well pump in which the ratio of operating fluid pressure so pumped fluid pressure will be the same 75 for strokes of the pump in opposite directions.

It is a further object of our invention to provide a fluid-motor deep well pump having a piston working in a barrel and being 80 operated, by clean oil or any other suitable operating fluid introduced into one end of the barrel, to move against well oil in the opposite end of this barrel, so that the clean oil, being at a higher pressure than the well 85 oil, will tend to leak around the piston and wash any sand particles from between the bearing surfaces of the barrel and the piston.

After once commencing the operation of the fluid-motor deep well pump, as briefly 90 described above, the pump tubing and the small operating oil pipe thereof are filled with oil. In case it is desired to remove

invention to provide a fluid-motor deep well pump which provides a novel bleeder for draining oil from the pump tubing and operating fluid pipe before drawing these from the well.

Another object of our invention is to provide a fluid-motor deep well pump having a novel fluid-operated plunger valve.

Yet another object of our invention is to provide a fluid-motor deep well pump having a novel mechanically operated control valve by which ports are controlled so as to admit operating fluid into operating relation with said fluid-operated valve.

It is very desirable in operating a fluid-motor pump that the flow of operating fluid to said pump and the flow of exhaust oil from said pump be kept as continuous as possible for the purpose of reducing the loss of energy occasioned by overcoming the inertia of the columns of operating fluid and exhaust oil when the speeds of their flow fluctuate.

Still another object of our invention is to provide a fluid-motor deep well pump having a gas cushion element disposed in the operating fluid pipe line which tends to absorb any tendency toward pulsation in the columns of operating fluid and exhaust fluid flowing to and from the pump.

Other objects and advantages will be made manifest in the following description and in the accompanying drawings in which:

Fig. 1 is a diagrammatic view illustrating a deep well in which a preferred embodiment of our pump is shown installed in a well with the necessary auxiliary equipment for operating the same.

Figs. 2 to 9, inclusive, are vertical sectional views of portions of the fluid-motor pump of our invention which are taken upon the same plane and which may be joined together in consecutive order to form a complete sectional view of our pump.

Fig. 10 is a vertical sectional view taken on the line 10—10 of Fig. 6.

Fig. 11 is a vertical sectional view taken on the line 11—11 of Fig. 7.

Fig. 12 is a vertical sectional view similar to Fig. 11 and illustrating the mechanically operated valve of our invention when shifted into its lowermost position.

Fig. 13 is an elevational view of the body base plug of our invention showing the manner in which certain pipes are attached thereto.

Figs. 14, 15 and 16 are horizontal sectional views taken on correspondingly numbered lines of Fig. 2.

Fig. 17 is a horizontal sectional view taken on the line 17—17 of Fig. 3.

Figs. 18 to 25, inclusive are horizontal sectional views taken on correspondingly numbered lines of Fig. 4.

Figs. 26 and 27 are horizontal sectional

views taken on correspondingly numbered lines of Fig. 5.

Figs. 31, 32 and 33 are horizontal sectional views taken on correspondingly numbered lines of Figs. 7 and 11.

Fig. 34 is a horizontal sectional view taken on the line 34—34 of Fig. 9.

Fig. 35 is a diagrammatic view illustrating the complete fluid-motor pump of our invention. This view is provided to assist in an understanding of the inter-relation of the many fragmentary views which are utilized to illustrate the detailed structure of the pump.

Figure 36 is a diagrammatic view illustrating the complete fluid-motor pump with the moving parts positioned differently than in Fig. 35.

Referring specifically to the drawings, 40 indicates a deep well in which a casing 41 is placed, the casing 41 being capped by a well casing head 42. Passing downward through the casing head 42 and disposed within the casing 41 is a pump tubing 43. The lower end of the pump tubing 43 is connected by a coupling 44 to the upper end of the fluid-motor pump 45 of our invention. The pump tubing 43 has a T 46 secured to it above the casing head 42 from which an exhaust pipe 47 leads to suitable storage (not shown). On the extreme upper end of the pump tubing 43 a stuffing-box 48 is provided. Passing downward through the stuffing-box 48 and throughout the length of the tubing 43 to where it joins to the motor pump 45 of our invention, as will be described later, is an operating fluid supply pipe 50. The upper end of the pipe 50 is connected to the pressure end of a high pressure pump 51 which draws a clean operating fluid from a source (not shown) and forces it into the upper end of the pipe 50.

The preferred embodiment of our fluid-motor pump 45, which is illustrated in section in Figs. 2 to 9 inclusive, has a body 55 which is composed of a shell 56 and a core 57. The shell 56 may be made up of several joints connected by couplings or it may be formed of a single piece of tubing as it is illustrated in the drawings. The core 57 is built up of a number of elements as will be made clear in the description.

The shell 56 has an up-set annular shoulder 59 formed at its upper end which has outer threads 60 to which the coupling 44 connects. Upper internal threads 61 and lower internal threads 62 are formed in the shoulder 59. A plug 63 formed at the lower end of a novel socket joint member 65 is threaded into the threads 61. The joint member 65 has a neck 66 which is formed upward from the plug 63 and threaded into the upper end of a sleeve 67. The sleeve 67 has a ground cylindrical face formed upon the inner surface of the walls 130

thereof and has outward flaring guide-prongs 70 upon the upper end 71 thereof. The lower end of the pipe 50 has a cylindrical tube 73 which is ground upon its outer surface to fit the cylindrical face 68 of the sleeve 67. The tube 73 also has a conical face 74 formed at its lower end which is adapted to engage a complementary conical seat 75 formed upon the upper end of the neck 66. The lower end of the pipe 50 is secured to the tube 73 by threads 77 and is drawn into sealed engagement therewith upon a pair of complementary conical faces formed upon these members, as indicated at 78.

A port 80 is formed in the coupling 44 and a port 81 is formed in the wall of the sleeve 67. A pipe 82 having a union 83 has its opposite ends welded into the ports 80 and 81 respectively. When the pump 45 of our invention is installed, it is lowered into the well 40 upon the lower end of the pump tubing 43. At this time the pipe 50 has not been placed in the tubing 43. The tube 73, however, has been disposed in the sleeve 67 so that communication between the exterior and interior of the tubing 43 through the tube 82 is prevented, thus the interior of the pump 45 is kept clean while it is being installed. The pipe 50 is then lowered through the tubing 43 and by rotation is screwed into the tube 73 at the threads 77 so that a seal is effected at the conical faces 78. When it is desired to remove the pump 45 for repairs, the pipe 50 may be elevated sufficiently to withdraw the tube 73 from the sleeve 67 sometime before the withdrawal of the pump tubing 43 from the well 40 is commenced. A passage is thus opened through the pipe 82 from the interior of the pump tubing 43 to the exterior thereof. This will allow the oil within the pump tubing 43 to drain outwardly through the pipe 82 into the bottom of the well 40, thus the pump tubing 43 will be empty when withdrawn from the well and a "wet job" will be prevented.

The core 57 has an upper tubular member 85 which is threaded into the thread 62 of the annular shoulder 59. The core 57 also has a lowermost tubular member 86 which is threaded joined at 87 to an eccentric base block projection 88 formed upward upon a body base plug 90. The lower end of the shell 56 is threaded joined to the plug 90 at 91.

The core 57 being of smaller diameter than the inside of the shell 56, a passage space 93 is formed between the core and the shell. This passage space 93 is sealed against communication with the outside of the shell 56 at its lower end by the base plug 90. Openings 95 are formed in the annular shoulder 59 of the upper end of the shell 56 and these openings provide a passageway between the space 93 and the interior of the pump tubing 43.

A gas cushion member 100 is formed in the upper end of the core 57, as shown in Fig. 3. The upper tubular member 85 of the core 57 proceeds downward a considerable distance and is threaded received at 101 in a coupling 102. A sleeve 103 is threaded received in the lower end of the coupling 102 and is threaded joined by a coupling 104 to a connecting nipple 105. The nipple 105 is threaded joined at its lower end by a coupling 106 to a tubular member 107. An inner tube 110 is threaded received at 111 in the plug 63 so as to communicate with the lower end of the neck 66. The upper inner tube 110 is of considerably smaller diameter than the inside of the member 85 and has a ground fit with the inner surface of the sleeve 103, the tube 110 terminating at its lower end in abutment with the nipple 105 and communicating with the interior passageway thereof. A lower inner tube 112 is threaded secured at its upper end in the lower end of the central passageway of the nipple 105 and depends downward therefrom to within a short distance of the lower end of the tubular member 107 where it threaded receives a cap 113. Openings 114 are provided in the lower end of the lower inner tube 112 and a screen 115 is wrapped about the tube 112 to cover the openings 114. Openings 117 are formed in the lower portion of the tubular member 85. The operation of the gas cushion member 100 will be described later.

The lower end of the tubular member 107 is threaded joined by a coupling 118 to a connector 119. A fluid operated plunger valve barrel 120 is threaded joined at its upper end to the connector 119. The valve barrel 120 has a cylindrical valve chamber 121 which has a threaded counter-bore 122 at its upper end in which is screwed a double ball check valve 123. The outer end of the threaded bore 122 is screwed upon the connector 119. A threaded counter-bore 125 is formed in the lower end of the valve chamber 121 and threaded receives a double ball check valve 126. The lower check valve 126 has an annular recess 127 formed in the body 128 thereof, which recess communicates through an opening 130 with the passage space 93. A secondary threaded counter-bore 131 is formed in the lower end of the valve barrel 120, this counter-bore receiving a lock nut 132 which secures the valve 126 in place in the counter-bore 125. The counter-bore 131 is of such length as to provide a cavity 133 below the nut 132, which cavity communicates with an opening 134 which is formed in the wall of the barrel 120. Operating fluid inlet ports 140 and 141 are formed in the wall of the barrel 120. The connector 119 has a central passageway 142 which communicates with a cavity 143 formed in the

counter-bore 122 between the connector 119 and the check valve 123.

Ports 144 and 145 are formed in the wall of the valve barrel 120 to communicate with the cavity 143. Connecting the port 144 with the ports 140 and 141 is an operating fluid supply pipe 146. Operating fluid ports 148 and 149 are formed in the wall of the barrel 120 opposite the ports 140 and 141 respectively. Operating fluid exhaust ports 150 and 151 are provided in the wall of the barrel 120 and ports 152 and 153 are formed in the wall of the barrel 120 opposite the ports 150 and 151 respectively.

15 A fluid operated valve plunger 160 is slidably disposed in the valve chamber 121 so as to make a fluid-tight fit therewith. In Fig. 4 the valve plunger 160 is shown in its upper position and disposed a given distance above the upper end of the lower check valve 126. Annular pockets 161, 162, 163, and 164 are formed in the outer surface of the plunger 160. When the plunger is in its upper position, as shown, the pocket 161 establishes communication between ports 140 and 148. The pockets 162 and 163 are not aligned with any ports. The pocket 164 establishes communication between the ports 151 and 153.

20 25 In Fig. 19 a valve operated opening 166 is shown formed in the wall of the barrel 120 communicating with the chamber 121 at the upper end thereof. In Fig. 24 a valve-operated opening 167 is shown formed in the wall 30 of the barrel 120 communicating with the lower end of the chamber 121.

35 A threaded upper end 170 of a head block 171 is screwed into the lower end of the threaded counter-bore 131. Eccentrically depending from the upper end 170 of the head block 171 is a stem portion 172, while threadedly secured at 173 upon the lower end of the stem 172 is an upper cylinder barrel 174. A passageway 175 is provided throughout the 40 length of the block 171 to communicate between the cavity 133 and the upper end of the upper piston chamber 177, which is formed in the upper cylinder barrel 174. The stem 172 is cut away at 178 to form an enlarged space 179 in the passage space 93 for a purpose which will be described later.

45 The lower end of the upper cylinder barrel 174 is threadedly secured at 184 to the upper end of an intermediate block 185. A piston rod bore 186 is formed centrally throughout the length of the intermediate block 185. An annular counter-bore 187 is formed in the upper end of the piston rod bore 186. A threaded opening 188 is formed in the intermediate block 185 to communicate between the exterior thereof and the counter-bore 187.

50 An upper pumped-fluid valve member 190 is disposed in the passage space 93 opposite the threaded opening 188. A central T 191 of the valve member 190 has a nipple 192 which

is threadedly received in the opening 188. A tubular cage 194 is threaded upon an upper nipple 195 of the T 191 and confines a ball 196 in seating relation with the upper end of the nipple 195. A connector 198 is threadedly received in the upper end of the cage 194 and has a cage 199 threadedly received upon its upper end to confine a ball 200 in seating relation with the upper end of the connector 198. A cage 202 is threadedly received upon a lower nipple 203 of the T 191 and has a connector 204 threadedly received in the lower end thereof so that a ball 205 is confined over a seat formed upon the upper end of the connector 204. A cage 207 is threadedly received upon the lower end of the connector 204 and a connector 209 is threadedly received in the lower end of the cage 207 so that a ball 210 will be confined over a seat formed upon the upper end of the connector 209. The connector 209 has a bonnet 212 threadedly received upon the lower end thereof which secures the upper end 213 of a pumped-fluid inlet pipe 214 to the connector 209.

55 Referring to Fig. 9, there is an opening 218 formed longitudinally through the body base plug, and a lower portion 220 of the pumped-fluid inlet pipe 214 is secured in the upper end thereof. A union 221 connects the upper and lower pipes 213 and 220. The balls 205 and 210 may be unseated by suction of pumped-fluid inward through the nipple 192, while the balls 196 and 200 will be seated by such a suction. Movement of pumped-fluid outward through the nipple 192 will cause a reverse action of these balls and permit the pumped fluid to be forced upward out of the cage 199 into the fluid passage space 93. The lower end of the intermediate block 185 is threadedly connected at 223 to the lower tubular member 86 of the body core 57. The lower tubular member 86 forms the lower piston cylinder 224 of our fluid-motor pump.

60 A counter-bore 225 is formed in the lower end of the piston rod bore 186. A threaded opening 227 is formed in the intermediate block 185 and communicates between the outside thereof and the counter-bore 225. A pumped fluid valve member 229, which is identical in structure to the valve member 190, is threadedly received into the threaded opening 227. Connected to the lower end of the valve member 229, in the same manner as the pipe 213 is connected to the valve member 190, is an upper pipe 230 of a pumped fluid inlet pipe 231. An opening 232 is provided longitudinally through the body base plug 90 and a lower pipe 233 of the pumped fluid inlet pipe 231 connects with the upper end of the port 232. A union 235 joins the upper and lower pipes 230 and 233.

65 An opening 238 is formed longitudinally through the body base plug 90 and the base block projection 88, the lower end of this

opening threadedly receiving a plug 239. A branch opening 240 is formed from the opening 238 in the body base plug 90, the branch 240 receiving the lower section 242 of a lower 5 piston cylinder operating fluid pipe 243. An upper section of pipe 244 is connected to the section 242 by a union 245 and rises upward through the passage space 93. For convenience in assembling, the upper pipe section 10 244 has a union joint 246 which is disposed in an enlarged portion of the passage space 93 formed by the recess 179. The upper end of the pipe 244 is connected to both of the ports 149 and 151 as shown in Fig. 4. Thus a passageway is provided between both of the ports 149 and 151, through the pipe 243 and the openings 240 and 238, into the lower end of a lower piston chamber 250 formed in the cylinder 224.

Referring to Fig. 4, an upper operated fluid conduit 252 connects to both of the ports 148 and 150, as shown, and provides a passageway between these ports and the opening 134 into which the lower end of the pipe 252 25 is secured. The passageway thus formed by the pipe 252 continues through the cavity 133 and the opening 175 into the upper end of the upper piston chamber 177, as shown in Fig. 5.

30 A plunger member 260 is disposed in the upper and lower piston chambers 177 and 250 and in the piston rod bore 186 which connects these chambers. The plunger member 260 comprises an upper piston 261 adapted to slide in the upper piston chamber 177, a lower piston 263 adapted to slide in the lower piston chamber 250, and a piston rod 264 which is adapted to slide in the piston rod bore 186 and which connects the pistons 261 and 263. 35 The piston rod 264 comprises a piston rod sleeve 266 which is threadedly received at its opposite ends in the inner ends of the pistons 261 and 263, and a tie rod 267 which is disposed within the sleeve 266 and which projects therefrom through central apertures in the pistons 261 and 263 to the outer ends of these pistons, where it threadedly receives nuts 270 which are turned down upon the outer ends of the pistons in cavities 271 40 and which connects the pistons 261 and 263. The piston rod 264 is adapted to reciprocate between lowermost and uppermost positions.

45 In Figs. 5 to 8 inclusive, the plunger member 260 is shown in substantially its uppermost position. A mechanically operated valve 275 rests in an annular pocket 276 formed in the outer surface of the piston rod 264. In the present embodiment this pocket 276 is formed by cutting out a portion of the 50 piston rod sleeve 266 and interposing a sleeve 278 of considerably smaller diameter than the sleeve 266 in place of the removed portion. The opposite ends of the sleeve 278 are threadedly received into the ends of the remaining upper and lower portions of the

55 sleeve 266. The mechanically operated valve 275 has a sleeve 280, the outer surface of which is ground to form a fluid-tight sliding fit with the surface of the bore 186. The valve sleeve 280 has upper and lower annular 60 pockets 281 and 282 formed in the outer surface thereof. The inside diameter of the sleeve 280 is greater than the outer diameter of the sleeve 278 so that the plunger member 260 may be shifted longitudinally relative to the valve sleeve 280 within the limits of the space 276 without the sleeve 280 being affected by movement of the plunger member 260 through pressure of any fluid which might be disposed in the space 276. Thus 65 when the plunger member 260 commences a downward movement from the uppermost position in which it is shown in Fig. 6, the sleeve 280 will remain in the position shown until its upper end is contacted by a shoulder 283 of the piston rod 264. Also, when the plunger member 260 commences an upward movement from the lowermost position in which it is shown in Fig. 12, the sleeve 280 70 will remain in the position shown until its lower end is contacted by a shoulder 2831 of the piston rod 260. Thus, the sleeve 280 and shoulders 283, 2831 together constitute one 75 form of lost motion connection between the piston rod and the valve 275.

80 The mechanically operated valve 275 is adapted to set up operating fluid circuits at each of the upper and lower positions of the plunger member 260 which will cause the reversal of the position maintained by the valve plunger 160 during the stroke of the plunger member, made while it was approaching that end position. For this purpose, upper and lower sets of ports are provided in the intermediate block 185 which open into the piston rod bore 186 and certain ones of which are connected by the pockets 281 and 282 to effect the circuits above mentioned. Referring to Figs. 10 and 11, it will be seen that an upper supply port 290 and a lower supply port 291 are connected by an operating fluid supply pipe 292 to the port 185 which receives operating fluid through the port 145 from the cavity 143. Connecting ports 295 and 296 are formed in the intermediate block 185, as shown in Figs. 10 and 11, which are connected by a pipe 297 to the port 167 formed in the plunger valve barrel 120 at the lower end of the plunger chamber 121. Connecting ports 300 and 301 are connected by a pipe 302 to the port 166 formed in the valve plunger barrel 120 to open into the upper end of the valve chamber 121. Exhaust ports 305 and 306 are formed in the intermediate block 185 to communicate with the piston rod bore 186 opposite the ports 300 and 296 respectively. 100

105 The operation of our invention is as follows:

110 Operating fluid is supplied to the pipe 50 130

by the pump 51 at any pressure desired, this preferably being about five hundred pounds to the square inch. This operating fluid flows downward through the pipe 50, the tube

- 5 73, the neck 66, the tube 110, the connector 105, the tube 112, the openings 114, the connector 142, and flows from the cavity 143 into the feed pipes 146 and 292. In Figs. 4 and 36 the valve plunger 160 is shown in 10 its upward position in which it sets up a circuit for causing the plunger member 260 to be moved from its upper to its lower position. The moving of the valve plunger to its upper position, as shown in Figs. 4 and 6, is effected 15 by an operating fluid circuit which is set up by the mechanically operated valve 275 by virtue of said valve 275 having been actuated to the position shown in Figs. 6 and 10 by the plunger shoulder 2831. The fluid operated valve actuating circuits thus set up are as 20 follows:

Operating fluid is admitted from the cavity 143, through the supply pipe 292, the port 290, the pocket 281, the port 295, the pipe 297, 25 and the port 167 to the lower end of the valve plunger chamber 121. The pressure of the operating fluid thus admitted into the lower end of the chamber 121 is intended to move the plunger 160 into the position in which it 30 is shown in Figs. 4 and 36. The fluid previously disposed above the plunger 160 was exhausted from the upper end of the chamber 121, through the port 166, the pipe 302, the port 300, the pocket 282, and the port 305 into the exhausted fluid passage space 93. Due to the plunger 160 being thus moved into its upper position a pump operating circuit is set up, as follows:

- Operating fluid flows from the pipe 146 40 through the port 140, the pocket 161, the port 148, the pipe 252, the opening 134, the cavity 133, and the opening 175 into the upper end of the upper piston chamber 177. Here the introduction of operating fluid tends to force 45 the plunger member 260 downward to the position shown in Fig. 35 by exerting a pressure upon the upper end of the piston 261. As the plunger member 260 goes downward, well oil, which has been drawn into the lower end 50 of the upper chamber 177, will be exhausted around the check balls 196 and 200 into the exhausted fluid passage space 93. Used operating fluid which is disposed in the lower end of the lower piston chamber 250 will be exhausted through the passage 238, the passage 240, the pipe 243, the pipe 151, the pocket 164 and the port 153 into the exhausted fluid passage space 93. Inasmuch as the operating fluid is maintained at a much greater pressure per square inch than the pressure of the fluid in the passage space 93, the movement of fluids is accomplished as just described. As 60 the plunger member 260 moves downward, the lower pair of check valve balls of the valve 229 are unseated to admit well oil up- 65

ward through the opening 218, the pipe 214, through the valve 229, the port 227 and the counter-bore 225 to the upper end of the lower piston chamber 250.

It will be noted in Fig. 6 that the space 276 is longer than the sleeve 280 disposed therein. This permits the sleeve 280 to remain in place so as to be sure to complete the throw of the plunger 160 before the circuits effecting this throw are cut off by downward movement of the sleeve 280. This insures positive action of our fluid-motor pump and prevents faulty functioning of the fluid-operating circuits set up by the mechanical valve 275 to move the fluid-operated plunger 160 to cause the reciprocation of the plunger member 260. When the plunger member 260 arrives at the lower position, shown in Fig. 35 the valve sleeve 280 is positioned as shown in Fig. 12, so that the pocket 281 communicates between the exhaust port 306 and the connecting port 296 of the pipe 297 so that fluid beneath the valve plunger 160 may be exhausted through the port 167, the pipe 297, the port 296, the pocket 281 and the port 306 into the exhaust fluid passage space 93. The pocket 282 communicates between the ports 291 and 301 so that operating fluid flows through the pipe 292, the port 291, the pocket 282, the port 301, the pipe 302, and the port 166 into the upper end of the valve chamber 121, thus moving the plunger 160 downward in the chamber 121 to the position shown in Fig. 35 so that the following circuits will be set up.

Fluid may now be exhausted from the upper end of the upper piston chamber 177 through the passage 175, the cavity 133, the opening 134, the pipe 252, the port 150, the pocket 163 and the port 152 into the exhausted fluid passage space 93. Operating fluid may now flow from the supply pipe 146 through the port 141, the pocket 162, the port 149, the pipe 243, the opening 240, and the opening 238, into the lower end of the lower piston chamber 250, thus causing the downward movement of the plunger member 260 to be halted and its upward movement commenced. The upward movement of the plunger member 260 continues until it has reached the position in which it is shown in Fig. 36 of the drawings, at which time the mechanically operated valve 275 will set up the circuits described which cause the plunger 160 to move into its upward position in which it is shown in Figs. 4 and 36. Thus a complete cycle of operation of our fluid-motor pump is ended and the pump parts are in position to commence automatically a second cycle. The pump is designed so that in event it should be shut off and stopped on dead center, it may be forced from dead center by a simple operation, which is as follows:

If for any reason should the power cease and the valve plunger 160 should be in such a position that all of the ports thereof are shut

off, the power fluid is reversed, that is, the tubing 43 is used as the power line and the operating fluid supply pipe 50 is used as the exhaust line. Fluid, under pressure, will 5 pass through the opening 130 in the plunger valve barrel 120, unseating the balls of the lower check valve 126. The fluid under pressure flows into the space in the barrel 120 below the valve 160 and forces it upward into 10 the position shown in Figs. 4 and 36 of the drawings. The upper check valve 123 is opened at this time and any operating fluid above the valve 160 will pass therethrough into the opening 142. This moves the valve 160 so that the ports are opened, whereafter the 15 power fluid may be forced through its proper line and the pump set into operation.

The shell and core construction of the body of our pump is of especial importance, as it 20 provides a fluid passage space which may not only be used for an exhaust fluid connecting passage but also as a piping space in which piping may be disposed to furnish all of the necessary longitudinal ducts for conveying 25 fluid over a considerable longitudinal distance in the fluid-motor pump. Such a structure eliminates all necessity for forming and roofing channels in the metal of the body for the purpose of providing these longitudinal ducts. This eliminates one of the 30 most expensive and objectional features of previously produced fluid-motor pumps.

It will also be noted that the double gas 35 pocket cushion structure is provided in the upper end of the core of the pump body. A gas pocket is thus provided to communicate with the column of operating fluid in the pipe 50 and another gas pocket is provided to communicate with the column of exhaust 40 fluid disposed in the pump tubing 43. These gas pockets tend to dampen any pulsation in the flow of operating fluid or exhausted fluid due to the reciprocating of the fluid-motor pump and thus bring about a relatively 45 continuous flow in the operating and exhausting columns of fluid. This is a feature of decided advantage inasmuch as an irregular flow of fluid absorbs a much greater quantity of energy than a continuous flow of the same 50 amount of fluid. This difference is due to the expenditure of energy necessary in overcoming the inertia of the fluid during the accelerating portion of each pulsation.

We claim as our invention:

1. In a deep well fluid-motor pump, the combination of: a body having an outer shell and a central core disposed within said shell to form a passage space between said core and said shell, there being formed in said core 55 a pair of aligned piston chambers and a piston rod bore connecting said chambers; pistons disposed in said chambers; a piston rod disposed in said bore and connecting said pistons; check-valved means for supplying a fluid to be pumped to the inner ends of said
2. In a deep well fluid-motor pump, the combination of: a body having an outer shell and a central core disposed within said shell to form a passage space between said core and said shell, there being formed in said core a pair of aligned piston chambers and a piston rod bore connecting said chambers; pistons disposed in said chambers; a piston rod disposed in said bore and connecting said pistons; check-valved means for supplying a fluid to be pumped to the inner ends of said piston chambers; check-valved means for permitting pumped fluid to be exhausted from the inner ends of said piston chambers into said passage space; a fluid-operated valve; means for conveying an operating fluid to said valve; conduit means connecting said fluid valve to the outer ends of said piston chambers, there being a passageway formed in said body to connect said fluid valve with said passage space; and a mechanically operated valve moved by said plunger member to admit operating fluid into shifting relation with said fluid valve so that said fluid valve will admit operating fluid into the outer end of one piston chamber and permit the exhaust of used operating fluid from the outer end of the opposite chamber 105 into said passage space so as to cause the automatic reciprocation of said plunger member.
3. In a deep well fluid-motor pump, the combination of: a body having a pair of aligned piston chambers and a piston rod 110 bore connecting said chambers; pistons disposed in said chambers; a piston rod disposed in said bore and connecting said pistons; check-valved means for supplying a fluid to be pumped to the inner ends of said piston chambers; check-valved means for permitting pumped fluid to be exhausted from the inner ends of said piston chambers; means including a valve positively operated by the piston rod for supplying an operating fluid alternately to the outer ends of said chambers to cause the reciprocation of said plunger member; and means permitting the exhaust of used operating fluid from the outer end of each of said chambers when operating fluid is being admitted into the outer end of the opposite chamber.
4. In a deep well fluid-motor pump, the combination of: a body having an outer shell and a central core disposed within said

- shell to form a passage space between said core and said shell, there being formed in said core a pair of aligned piston chambers and a piston rod bore connecting said chambers; pistons disposed in said chambers; a piston rod disposed in said bore and connecting said pistons; check-valved means for supplying a fluid to be pumped to the inner ends of said piston chambers; check-valved means for permitting pumped fluid to be exhausted from the inner ends of said piston chambers into said passage space; a fluid-operated valve; means for conveying an operating fluid to said valve; conduit means connecting said fluid valve to the outer ends of said piston chambers, there being a passageway formed in said body to connect said fluid valve with said passage space; and a mechanically operated valve provided upon said piston and moved by said plunger member in said piston bore to admit operating fluid into shifting relation with said fluid valve so that said fluid valve will admit operating fluid into the outer end of one piston chamber and permit the exhaust of used operating fluid from the outer end of the opposite chamber into said passage space so as to cause the automatic reciprocation of said plunger member.
5. A deep well fluid-motor pump comprising: a shell; a core disposed in said shell and secured thereto at its opposite ends to form an exhaust passage space between said shell and said core, there being formed in said core a pair of piston chambers, a piston rod bore connecting said piston chambers, and a fluid-operated valve chamber; a plunger member comprising pistons disposed in said piston chambers and a piston rod disposed in said piston rod bore and connecting said pistons; a fluid-operated valve plunger disposed in said valve chamber; an operating fluid supply means; a pipe disposed in said passage space and connecting said supply means with said valve chamber; pipes disposed in said exhaust passage space and connecting said valve chamber to the outer ends of said piston chambers, a port being formed joining said valve chamber to said exhaust passage space; check-valved pipes disposed in said passage space and connecting the inner ends of said piston chambers with the exterior of said shell for supplying fluid to be pumped to said chambers; check-valved pipes connecting the inner ends of said piston chambers with said exhaust passage space; an exhaust conduit connecting with said exhaust passage space; a mechanically operated valve sleeve mounted upon said piston rod to slide in said piston bore with the reciprocation of said plunger member; and pipes disposed in said exhaust passage space and connecting said operating fluid supply means with said piston bore and connecting said piston bore with the ends of said valve chamber.
6. A combination as in claim 5 in which said operating fluid supply means comprises a vertical tube disposed axially within said exhaust conduit and having: a sleeve disposed about said tube and spaced therefrom and sealed thereto at its upper end and medially downward therefrom to form an upper chamber and a lower chamber, ports being formed in said sleeve to communicate between the lower end of the upper chamber and said exhaust conduit, said tube terminating near the lower end of said lower chamber and said sleeve being connected to said pump at the lower end thereof.
7. A deep well fluid-motor pump having: a body, there being formed in said body a pair of aligned piston chambers connected by a piston rod bore; a plunger member comprising pistons slidably disposed in said chambers and a piston rod slidably disposed in said piston rod bore and connecting said pistons; an operating fluid supply means; fluid operated valve means for admitting operating fluid into outer ends of said chambers to reciprocate said plunger member; a mechanical valve comprising a sleeve resting in an annular cavity formed in the surface of said piston rod and fitting the surface of said bore, there being annular pockets formed in the outer surface of said sleeve, and ports formed in said body opening into said piston rod bore, so that certain of said ports are connected by said pockets toward the end of the strokes of said plunger member; conduit means connecting certain of said ports with said fluid supply means and other of said ports with said fluid operated valve means so as to admit operating fluid into operating relation with said fluid operated valve means when said plunger member near the ends of its strokes, and valved inlets and outlets for the piston chambers.
8. A deep well fluid-motor pump having: a body, there being formed in said body a pair of aligned piston chambers connected by a piston rod bore; a plunger member comprising pistons slidably disposed in said chambers and a piston rod slidably disposed in said piston rod bore and connecting said pistons; an operating fluid supply means; fluid operated valve means for admitting operating fluid into outer ends of said chambers to reciprocate said plunger member; mechanical valve means connected with and operated by movement of said plunger member to bring said operating fluid supply means into operative relation with said fluid operated valve means as said plunger member approaches the limits of its stroke so as to cause the automatic reciprocation of said plunger member; and check valve means connected to the inner ends of said chambers whereby well fluid may be pumped when said plunger member reciprocates.
9. A deep well fluid-motor pump having:

a body, there being formed in said body a pair of aligned piston chambers connected by a piston rod bore; a plunger member comprising pistons slidably disposed in said chambers and a piston rod slidably disposed in said piston rod bore and connecting said pistons; an operating fluid supply means; operating fluid valve means controlled by movement of said plunger member so that said means admits operating fluid alternately into the outer ends of said chambers so as to cause the automatic reciprocation of said plunger member; and check valve means connected to the inner ends of said chambers whereby well fluid may be pumped when said plunger member reciprocates.

10. A deep well fluid-motor pump having: a body, there being formed in said body a pair of aligned piston chambers connected by a piston rod bore; a plunger member comprising pistons slidably disposed in said chambers and a piston rod slidably disposed in said piston rod bore and connecting said pistons; an operating fluid supply means; fluid operated valve means for admitting operating fluid into outer ends of said chambers to reciprocate said plunger member; mechanical valve means operated by movement of said plunger member to bring said operating fluid 20 supply means into operative relation with said fluid operated valve means as said plunger member approaches the limits of its stroke so as to cause the automatic reciprocation of said plunger member, said mechanical 25 valve means having lost motion relative to said plunger member to insure actuation of said fluid operated valve means; and check valve means connected to the inner ends of said chambers whereby well fluid may be 30 pumped when said plunger member reciprocates.

11. A deep well fluid-motor pump having: a body, there being formed in said body a pair of aligned piston chambers connected by a piston rod bore; a plunger member comprising pistons slidably disposed in said chambers and a piston rod slidably disposed in said piston rod bore and connecting said pistons; an operating fluid supply means; fluid operated valve means for admitting operating fluid into outer ends of said chambers to reciprocate said plunger member; mechanical valve means operated by movement of said plunger member to bring said operating fluid 45 supply means into operative relation with said fluid operated valve means as said plunger member approaches the limits of its stroke so as to cause the automatic reciprocation of said plunger member; check valve means connected to the inner ends of said chambers whereby well fluid may be pumped when said plunger member reciprocates; exhausted fluid conduit means for conducting fluid from said fluid motor pump; and emergency valve 50 means whereby said fluid operated valve 55

means may be moved to a given operative position by reversing the direction of flow of fluid through said exhausted fluid conduit means and said operating fluid supply means.

12. A deep well fluid-motor pump comprising a body having an outer shell and a core disposed within said shell to form a passage space between the core and shell, there being formed in said core a pair of aligned piston chambers and a piston rod bore connecting said chambers, pistons disposed in said chambers, a piston rod disposed in said bore and connecting said pistons, check-valved means for supplying a fluid to be pumped to one end of each piston chamber, check-valved means for permitting pumped fluid to be exhausted from each of said ends into said passage space, means for supplying an operating fluid alternately to the other ends of said chambers to cause the reciprocation of the plunger member, and means permitting the exhaust of used operating fluid from said other ends into said passage space when operating fluid is being admitted into the first mentioned end of the opposite chamber, and a mechanically operated valve moved by the plunger member and controlling the flow of an operating fluid to and from the operating fluid supply and exhaust means.

13. A deep well fluid-motor pump comprising a body having an outer shell and a core disposed within said shell to form a passage space between said core and said shell, there being formed in said core a pair of aligned piston chambers and a piston rod bore connecting said chambers, pistons disposed in said chambers, a piston rod disposed in said bore and connecting said pistons, check-valved means for supplying a fluid to be pumped to one end of each of the piston chambers, check-valved means for permitting pumped fluid to be exhausted from said end of each piston chamber into said passage space, a fluid-operated valve, means for conveying on operating fluid to said valve, conduit means connecting said fluid valve to the other ends of the piston chambers, said body provided with a passageway connecting the fluid-operated valve with the passage space, and a mechanically operated valve moved by the plunger member to admit operating fluid into shifting relation with the fluid-operated valve so that said fluid-operated valve will admit operating fluid into one of the piston chambers and permit the exhaust of used operating fluid from the opposite chamber into said passage space to effect automatic reciprocation of the plunger member.

14. A deep well fluid-motor pump comprising a body having an outer shell and a core disposed within said shell to form a passage space between the core and the shell, there being formed in said core a pair of aligned piston chambers and a piston rod bore connecting said chambers, pistons dis-

- posed in said chambers, a piston rod disposed in said bore and connecting said pistons, check-valved means for supplying a fluid to be pumped to one end of each of the piston chambers, check-valved means for permitting pumped fluid to be exhausted from said end of each chamber into said passage space, a fluid-operated valve, means for conveying an operating fluid to said valve, 10 conduit means connecting the fluid-operated valve to one end of each piston chamber, said body provided with a passageway to connect the fluid-operated valve with said passage space, and a mechanically operated valve provided upon said piston and moved by the plunger member in said piston bore to admit operating fluid into shifting relation with the fluid-operated valve so that said fluid-operated valve will admit operating 20 fluid into one of the last mentioned ends and permit the exhaust of used operating fluid from the other of said last mentioned ends into the passage space to effect automatic reciprocation of the plunger member. 25 15. A deep well fluid-motor pump comprising a shell, a core disposed in said shell and secured thereto at its opposite ends to form an exhaust passage space between the shell and the core, there being formed in said core a pair of piston chambers, a piston rod bore connecting said piston chambers and a fluid-operated valve chamber; a plunger member comprising pistons disposed in piston chambers and a piston rod 30 disposed in the piston rod bore and connecting said pistons; a fluid-operated valve plunger disposed in the valve chamber; an operating fluid supply means; a pipe disposed in said passage space and connecting said supply means with said valve chamber; pipes disposed in said exhaust passage space and connecting said valve chamber to the outer ends of said piston chambers, a port being formed joining said valve chamber to 35 said exhaust passage space; check-valved pipes disposed in said passage space and connecting one end of each piston chamber with the exterior of the shell for supplying an operating fluid to said chamber; check-valved pipes connecting the said ends of the piston 40 chambers with the exhaust passage space; an exhaust conduit connecting with the exhaust passage space; a mechanically operated valve sleeve mounted on the piston rod to 45 slide in the piston bore with the reciprocation of the plunger member; and pipes disposed in the exhaust passage space and connecting the operating fluid supply means with the piston bore and connecting said piston bore with the ends of the valve chamber. 50 55 60 16. A deep well fluid-motor pump comprising spaced operating liquid and exhaust liquid conduits, one inside of the other, and a tube between said conduits sealed at its ends and provided with a port near its lower end

communicating with the bore of the outer conduit to harmonize fluctuations in the resistance to passage of liquid through said outer conduit and cause a substantially uniform flow of liquid through said outer conduit. 70

In testimony whereof, we have hereunto set our hands at Los Angeles, California, this 15th day of July, 1926.
